UNITED STATES PATENT OFFICE.

HENRY C. RICHARDSON, OF RICHMOND, VIRGINIA, ASSIGNOR OF ONE-HALF TO
WILLIAM C. NOLAND, OF RICHMOND, VIRGINIA.

GRIpper FOR PRINTING-PRESSES.

1,168,675.

Specification of Letters Patent. Patented Jan. 18, 1916.

Application filed August 11, 1914, Serial No. 856,176. Renewed December 10, 1915. Serial No. 66,222.

To all whom it may concern:

Be it known that I, HENRY C. RICHARDSON, residing at Richmond, in the county of Henrico and State of Virginia, have invented certain new and useful Improvements 5 in Grippers for Printing-Presses, of which the following is a specification.

This invention, which relates generally to improvements in grippers for printing 10 presses and the like, in which the coöperating parts are designed and combined that both the longitudinal and lateral adjustments of the gripper may be simultaneously made and the said parts so constructed that 15 the gripper may be used on narrow edged margins in such manner that the gage pins will not interfere with the application of the gripper to the paper, more specifically has reference to means on that form of gripper 20 device shown in Patent Number 927853, dated July 13, 1909.

From practical experience with the form of gripper disclosed in the patent referred to, I have found that while the same is generally effective for the purpose for which 25 it is provided, that under some conditions, especially when the paper to be held on the platen is very thin, that the paper holding gripper bars, by reason of being so mounted 30 upon and movable with the carriage attachment to the oscillatable gripper bar, that their under or contacting surfaces are so projected over the platen in a plane with the upper surface of the platen that the said 35 bars do not contact with the paper sheet under sufficient pressure to hold the sheet in the desired position on the platen during the operation of printing. Again in the construction of the gripper bar described in

40 the patent referred to, the hinged extensions of the gripper or paper holding bars are adapted for only two adjustments, one in the longitudinal direction of the bars and the other at right angles to the said bars.

45 My invention among other objects has for its purpose to provide certain improved features in the construction of the gripper or paper holding bars whereby to provide for causing the said bars to contact or press down upon the sheet to be printed, to positively hold, even the thinnest paper sheets 50 in proper position upon the platen during the printing operation; an improved connection for joining the hinged extensions of

the said paper gripper bars being also provided to permit for adjusting the extensions to project them to positions other than the straight-ahead and the right angled positions hereinbefore referred to.

With other objects in view that will hereinafter appear, my invention consists in the peculiar construction and novel arrangement of parts, all of which will be herein-after fully explained, specifically pointed out in the appended claims and illustrated 65 in the accompanying drawings, in which:

Figure 1 is a perspective view of my invention and shows the same as applied for use. Fig. 2 is a plan view of the printing press platen and the oscillatable gripper bar 70 with my improvements applied, the hinged extension of the paper gripper or pressure bar being shown adjusted diagonally with respect to the body of the said pressure bar. Fig. 3 is a plan view of the paper gripper 75 bar, constructed in accordance with my invention. Fig. 4 is a longitudinal section taken substantially on the line 4-4 on Fig. 2.

To render the operation and advantages 80 of my improved gripper device readily understood, I have illustrated, in the drawing, so much of the platen of a printing press and the oscillatable gripper, both of the usual construction, as is necessary to show 85 the practical application of my improved gripper bar.

In the drawing, 1 represents the oscillatable gripper having the usual flange 5 and trunnions 2 that journal in the bracket bearings 3 to which the platen 6, is connected and which has the usual gage pins 7, as shown.

9-9 designate the gripper or paper holding bars and they, in my construction, have 95 a longitudinal slot 11, to form relatively longitudinal and narrow rod like resilient members 10-10, and they are slidably held on a carriage 20 by the inturned fingers 20^a that form a part of the said carriage, as 100 shown.

The carriage 20 is slidably mounted on the bar 1 and is secured thereon by a bolt 22 that passes through the slot 4 in the bar 1 and through the longitudinal slot 11 in the 105 paper engaging bar 9 and the said bolt carries a washer 23 and nut 24 to secure the carriage to the gripper bar 9 and the presser

bar 9 to the carriage in their adjusted positions.

In the patent above referred to, the carriage 20, the bar 1 and the presser members 9, are relatively so connected and arranged that the members 9 when at their operative position lie flat-wise on the platen with their under or paper engaging faces held over the platen to move smoothly thereover, or in 10 other words to project flat-wise over the paper but without a pressure sufficient to positively prevent the thin paper sheets from buckling or slipping from under the said bars during the printing.

15 In my construction, the gripper or presser bars, which are projected from the carriage as in the patent referred to, have a portion 90 thereof, preferably the outer end bent down in a plane below the top face of the 20 carriage members to which they are connected, and by reason of such construction, a portion of the said presser or gripper bars when clamped on the carriage to their operative position, is positively held down adjacent the platen to produce a positive contacting of the said bars on the sheet, no matter how thin the paper, and under pressure sufficient to prevent the sheet from slipping from under the bars.

30 In my construction of the presser or gripper bar 9, the same has a quadrant shaped recess 9' in the inner edge of the outer end that forms a seat for receiving the semi-circular shaped ear 14^a formed on the inner 35 end of the extension 14 that is secured by a screw 17 to produce a hinge joint, and the said extension 14 has a shouldered portion 16 that forms a stop for engaging with the outer edge 95 of the arm 9 to hold the extension swung out to the longitudinal position, as shown in Fig. 1.

The extension 14 in my construction has a spring 17^a attached thereto, the free end of which extends over the adjacent end of 45 the bar 9 and has a snap stud 17^b for springing into engagement with any one of a series of lock apertures 96 in the bar to thereby provide for adjusting the arm either in the longitudinal plane of the bar, as is indicated in Fig. 1 at right angles thereto, as is shown in Fig. 3 or projected at an angle of 45 degrees to the said bar 9 as is shown in Fig. 2. By reason of providing the extension 14 and making it adjustable 50 as stated, should the printing be such that the edge gripping of the paper cannot be had and should there be a blank or open space along the said edge, the member 14 can be swung inwardly at an angle to the bar to engage the said sheet, while the said

bar is held away from engagement therewith.

From the foregoing description, taken in connection with the accompanying drawings, it is thought the complete construction, 65 operation, and advantages of my invention will be clear to those skilled in the art to which it appertains.

What I claim is:—

1. A gripper for printing presses consisting of a bar, a carriage in which the said bar is longitudinally adjustable, means for adjustably securing said bar and the said carriage to the gripper bar of a printing press, an extension piece hinged to the free end of the bar, the said bar extending beyond the hinged joint and having a plurality of latch recesses and a spring latch carried by the said extension piece having a lug to enter either of the said recesses to hold said extension piece in any of its different adjustments. 70

2. In a printing press, the combination with the platen and an oscillatable gripper bar that cooperates with the said platen, of a gripper, a carriage longitudinally slideable on said gripper bar, the said gripper comprising a flat member and projected from the carriage to lie flat-wise over the platen and a single means for adjustably securing said gripper member and the carriage to the gripper bar, that portion of the gripper member that moves over the platen being bent in two planes, one of which is below the top face of the carriage to which 95 the member is secured.

3. A gripper for printing presses consisting of a bar, a carriage on which the said bar is longitudinally adjustable, means for adjustably securing the said bar and the said carriage to the gripper bar of a printing press, the outer end of the said bar having a quadrant shaped recess on the inner edge thereof, an extension that includes a semi-circular shaped ear having a shouldered portion that forms a stop for engaging the outer edge of the gripper bar to hold the extension swung up lengthwise of the said bar, the said semi-circular shaped ear of the extension being pivotally mounted in the 105 aforesaid recess of the bar, said bar having a plurality of latch recesses and a spring latch carried by the extension and having a lug for engaging either of the latch recesses 110 for holding the extension piece in any of its 115 different adjustments.

HENRY C. RICHARDSON.
